UNITED STATES PATENT OFFICE.

JOSEPH DAVIDS, OF GENEVA, NEW YORK, ASSIGNOR TO PHILLIPS & CLARK STOVE CO.,
OF GENEVA, NEW YORK, A CORPORATION OF NEW YORK.

DESIGN FOR A STOVE.

40,964.

Specification for Design.

Patented Nov. 1, 1910.

Application filed August 10, 1910. Serial No. 576,609. Term of patent 7 years.

To all whom it may concern:

Be it known that I, JOSEPH DAVIDS, a citizen of the United States, residing at Geneva, in the county of Ontario and State of New York, have invented a new, original, and ornamental Design for Stoves, of which the following is a specification, reference being had to the accompanying drawing, forming a part thereof.

The figure is a perspective view of the new design.

The design consists in the form and configuration of the legs 1, the base 2 to which said legs are attached as shown, and also the configuration, shape and proportion of the ash box 3. Above the ash box an equatorial band 4 is placed with raised figures formed thereon with cut out places between such figures as shown at 4, with foot rests 5 attached to such equatorial band also provided with raised configuration. The fuel

door 6 is provided with openings which serve the purpose of checking drafts, but are formed with scroll edges for the purpose of beauty as shown. The top of the stove is completed by a plain band 7 and figured dome 8 with ornamental top 9 and urn 10 emplaced thereon.

In addition to the specific ornamental features pointed out, the design consists in the general form, shape and configuration of the stove considered as a whole which is amplified and emphasized by the specific ornamentation applied thereto as specified.

I claim—

The ornamental design for a stove as shown and described.

JOSEPH DAVIDS.
